CLAIM

We claim the ornamental design for a grill hood, as shown and described.

DESCRIPTION

FIG. 1 is a front perspective view of the grill hood;

FIG. 2 is a front view thereof;

FIG. 3 is a right side view thereof, the left side view being a mirror image of the right side view; and,

FIG. 4 is a top view thereof.

The bottom view is devoid of ornamentation.

The portions of the grill hood shown in broken lines are shown for illustrative purposes only and form no part of the claimed design.
